UNITED STATES PATENT OFFICE.

JOHN S. SCHEIDELL, OF PHILADELPHIA, PENNSYLVANIA, ASSIGNOR, BY DIRECT AND MESNE ASSIGNMENTS, TO THE CAMPBELL PRINTING PRESS AND MANUFACTURING COMPANY, OF NEW YORK, N. Y.

DELIVERY APPARATUS FOR PRINTING-PRESSES.

SPECIFICATION forming part of Letters Patent No. 323,215, dated July 28, 1885.

Application filed October 8, 1883. (No model.)

To all whom it may concern:

Be it known that I, JOHN S. SCHEIDELL, a citizen of the United States, and a resident of Philadelphia, Pennsylvania, have invented a 5 certain Improvement in the Delivery Apparatus of Printing-Presses, of which the following is a specification.

My invention consists of certain improvements, fully described and claimed hereinafter, 10 in the delivering mechanism of printing-presses of the character of which the "Campbell" press is an example, and which deliver the printed sheets face downward upon the delivery-table, the object of my improvement 15 being to deliver the sheet face upward.

In the accompanying drawings, Figure 1, Sheet 1, is a side view of sufficient of a printing-press to illustrate my invention. Fig. 2, a plan view of the same; Fig. 3, Sheet 2, a 20 transverse section, partly in elevation, of fly-operating mechanism; Fig. 4, a section on the line 1, 2, Fig. 3; and Figs. 5, 6, and 7, detached views of parts of the said fly-operating mechanism.

25 Referring in the first instance to Figs. 1 and 2, A represents the impression-cylinder of the press; B, part of the feed-table; D, the bed; E, inking-rollers; and F, the fly-frame for receiving the printed sheets from the impression- 30 cylinder and laying them upon the delivery-table G.

The spindle of the fly-frame has a pulley, a, around which passes a belt, b, from a drum, d, on a shaft, f, this drum being oscillated by 35 the cam mechanism hereinafter described and heretofore used in this class of presses, so as to impart the desired intermittent vibrating movement to the fly-frame F.

As the fly-frame F receives the sheet from 40 the cylinder A with the printed face upward, it delivers it upon the table G face downward, which is a serious objection, as it prevents the pressman from exercising a proper supervision of the work, especially when, as in modern practice, one pressman has charge of a number of presses. This objection I overcome by the use of a supplementary fly-frame, J, arranged in the rear of the frame F, and caused to vibrate in such relation thereto as

to receive the printed sheet therefrom and deliver it onto the table, the sheet being thus reversed and delivered face upward. 50

The movement of the frame J must follow that of the frame F—that is to say, the frame J must be in the position shown by dotted 55 lines before the frame F completes its movement in the direction of the arrow, and must remain in this position until the frame F has moved back to receive a new-printed sheet. This movement of the frame J is effected by a 60 supplementary drum, K, the shaft f' of which is geared to the shaft f by bevel-wheels g and a transverse intermediate shaft, h, although the shafts f f' may be connected by a belt and pulleys, if desired, the bevel-gearing being preferred, however, as being more positive in its 65 action than the belt.

The two flies are actuated by precisely similar mechanisms, that shown in Sheet 2 of the drawings being the mechanism for one of the 70 flies.

The drum d is loose on the shaft; but a disk, m, is secured thereto, and in this disk is a cam-slot, n, to which is adapted an anti-friction roller, p, on an arm, M, pivoted at its lower 75 end to a stud, s, and connected at the upper end to one end of a link, t, the opposite end of the latter being connected to a bolt, v, which is adjustable in an inclined slot, x, in the drum, and can be secured after adjustment. As the arm M is vibrated by the action 80 of the cam n, a movement of partial rotating, first in one direction and then in the other, will be imparted to the drum.

In the lower portion of the flange w of the 85 drum is a recess, y, for the reception of the arm M, said recess being of such extent that the arm will not interfere with the movements of the drum.

It should be understood that the above description of the mechanism has been introduced for the purpose of explaining my invention, and not with the view of laying any claim to it, for this fly-actuating mechanism is well known and in common use. 9c

As regards the prior state of the art, it should be remarked that prior to my invention sheets have been delivered printed-face

upward from a printing-press, a device for this purpose being shown in the patent of G. Jaeger, No. 246,514, August 30, 1881.

I claim as my invention—

5 The combination, in a printing-press, of two fly-shafts, *ff'*, each carrying a drum, to which an oscillating motion is imparted from the said shafts, two flies, one actuated from the drum of one shaft and the other from the drum of 10 the other shaft, and gearing whereby the two

shafts operate in unison and cause the flies to co-operate one with the other, all substantially as set forth.

In testimony whereof I have signed my name to this specification in the presence of two sub- 15 scribing witnesses.

JNO. S. SCHEIDELL.
